UNITED STATES PATENT OFFICE

2,510,226

PIVOTED LEVER CROWN CAP REMOVER

Frank Hooks, Jr., Chicago, Ill.

Application March 17, 1947, Serial No. 735,126

3 Claims. (Cl. 81—3.36)

1

The present invention relates to new and useful improvements in can and bottle openers and more particularly to a cutter adapted to travel around the beading of a can to sever the top thereof, the travelling movement of the cutter being accomplished by a pivoted handle and also to provide a bottle opener operated by said handle.

An important object of the present invention is to provide a combined can and bottle opener in which the several functions of the device are accomplished by a hand gripping action moving a pivoted handle toward a stationary handle.

A further object of the invention is to provide a tool of this character including a can opener including a toothed wheel for travelling under the beading of a can together with means for rotating the wheel and means for raising and lowering the wheel into and out of gripping engagement with the beading.

Another object is to provide a can locking device to secure the wheel in gripping engagement with the bead of the can.

A further object is to include in a tool of this character a bottle opening device including means for gripping the neck of the bottle and tilting the same while the cap is held stationary to thus force the cap from the bottle.

Another object is to provide a tool of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view.

Figure 2 is an enlarged fragmentary longitudinal sectional view.

Figure 3 is a similar view showing a bottle cap in position for removal.

Figure 4 is a transverse sectional view taken on a line 4—4 of Figure 2.

Figure 5 is a bottom plan view.

Figure 6 is a side elevational view showing the wheel in position for engaging the flange of a can, and

Figure 7 is a perspective view of a modified construction with parts broken away and shown in section.

Referring now to the drawings in detail and first with respect to the form of the invention

2

illustrated in Figures 1 to 5 inclusive, the numeral 5 designates a handle of substantially channel shaped construction and positioned with the open edge of the handle disposed downwardly, the handle adjacent its front end being formed with a cylindrical chamber 6 open at its bottom and the handle further being formed with an extension 7 projecting forwardly of the chamber 6.

10 The extension 7 includes side walls 8 and a top 9 and also with a cutter or blade 10 formed at the front end of the extension and extending downwardly from the top 9 as shown more clearly in Figure 2 of the drawings. The lower central portion of the blade 10 is pointed as shown at 11 and the lower edge of the blade is bevelled from the point outwardly toward the side thereof as shown at 12. The front ends of the side walls 8 of the extension 7 are bent inwardly to form opposed flanges 13 having a vertical opening 14 therebetween, the flanges being positioned rearwardly of the cutter 10 to provide working space for a toothed wheel 15 therebetween.

15 The wheel 15 is secured to the front end of a shaft 16 which is journalled in the sides of an inverted U-shaped bearing hanger 17 having a pair of spaced apart upstanding ears 18 projecting upwardly therefrom for pivotally supporting the bearing on a transverse pin 19 supported in the sides 8 of the extension 7.

20 The rear end of the shaft 16 is formed or provided with an annular flange 20 having teeth 21 projecting from its front face to engage the rear face of a pulley 22 rotatably mounted on the shaft

25 and held in engagement against the teeth 21 by a coil spring 23 positioned between the bearing 17 and the front face of the pulley. The teeth 21 function as clutch teeth for gripping the pulley to rotatably connect the pulley to the shaft upon

30 rotation of the pulley in one direction and providing for the free rotation of the pulley on the shaft upon rotation of the pulley in an opposite direction to thus rotate the wheel 15 in the same direction by a back and forth rotary movement of the pulley.

35 Figure 6 is a side elevational view showing the wheel in position for engaging the flange of a can, and

40 Figure 7 is a perspective view of a modified construction with parts broken away and shown in section.

45 A rope or cable 24 is trained over the pulley 22 with one end of the cable secured to the pulley and the other end thereof extending downwardly from the pulley and secured to an arm 25 carried at the front end of a handle 26 pivoted intermediate its ends to the sides of the stationary handle 5 by a transverse pin 27. A wire spring 28 is coiled intermediate its ends as at 29 and mounted on the pin 27 between the sides of the handle 5, the ends of the spring bearing respectively against the opposed surfaces of the handles

5 and 26 to move the handle 26 downwardly with respect to the handle 5. The handle 26 is closed against the handle 5 by a gripping action subjected to the handle.

Accordingly, by an opening and closing movement of the handle 26 relative to the handle 5 a pulling action will be subjected to the cable 24 whereby to rotate the pulley 22 and shaft 16 as well as the wheel 15 secured to the shaft. By penetrating the cutter 10 through the top 30 of a can 31, and engaging the toothed wheel 15 under the beading 32 of the can and by rotating the wheel 15 in the manner indicated, the cutter 10 will travel around the edge of the can to thus sever the top thereof.

In order to raise and lower the wheel 15 for positioning the same under the beading 32 I provide a lift arm 33 having an eye 34 at its lower end in which the shaft 16 is freely rotated, the arm extending upwardly through an opening 35 in the top 9 of the can opener and the upper end of the arm is pivoted to the front end of a lever 36 by means of a pin 37. The rear end of the lever extends upwardly to facilitate finger gripping engagement therewith. The underside of the lever 36 at its pivoted end is formed with a cam 38 bearing against the upper surface of the top 9 of the can opener, the cam being constructed to rock on the top 9 by a raising and lowering movement of the lever, a raising movement of the lever lowering the lift arm 33 and shaft 16 in the opening 14 between the flanges 13 whereby to lower the wheel 15 into a position for engaging under the beading 32 of the can. A lowering movement of the lever 36 will raise the shaft 16 and wheel 15 into tight gripping engagement with the beading 32.

A coil spring 39 positioned on the arm 33 between the eye 34 and the underside of the top 9 exerts its influence in a direction to move the shaft 16 and wheel 15 downwardly upon raising the lever 36.

The arm 33 is constructed of extensible threadedly connected sections as shown at 40 to provide for the longitudinal adjustment of the arms.

The forward portion of the handle 26 is constructed to form a ring 41 mounted for vertical movement in the chamber 6, the ring being adapted to receive the neck of a bottle inserted upwardly into the chamber.

A lug 42 is secured at one end to the underside of the top 9 of extension 7 by means of a bolt or nut 43, the other end of the lug projecting into the chamber 6, as shown in Figure 2 of the drawings.

The stationary lug 42 is provided with a downwardly extending stop 42a adapted for engagement by one side of a bottle cap 42b on the neck of a bottle inserted upwardly through the ring 41 and a diametrically opposite edge of the cap adapted for engagement by a pivoted lug 43' having one end pivoted on a pin 44 carried at the front end of a lever 45 which is pivoted intermediate its ends on a pin 46 extending transversely between the sides of the stationary handle 5. The rear end of the lever 45 is bifurcated as shown at 47 and in which is positioned a pin 48 carried transversely by the pivoted handle 26. The pivotal movement of the handle 26 thus swings the lever 45 vertically.

The lug 43' is yieldably held against the cap 42b by a wire spring 49 secured to the lever 45 by a pin 50 and the lower edge of the free end of the lug 43' is formed with a slotted shoulder 51 adapted for engagement under the edge of

the bottle cap when the lug 43 is swung upwardly, as shown in Figure 3.

The free end of the lug 43' projects radially inwardly of the ring 41 and accordingly in the operation of the bottle opener insertion of the neck of the bottle through the ring 41 will engage the free end of the lug 43' and thus swing the same upwardly to engage the shoulder 51 under the edge of the bottle cap at one side of the cap while the stop 42a engages the diametrically opposite side of the cap. An upward movement of the handle 26 will move the ring 41 downwardly thereby tilting the neck of the bottle engaged therein rearwardly to thus pry the cap from the bottle.

In Figure 7, I have illustrated a modified form of the invention which comprises a bottle cap opener per se having a stationary handle 52 provided with the chamber 53 open at its bottom for receiving the neck of a bottle and in which the stationary lug 54 and stop 55 are secured. A pivoted handle 56 is attached to handle 52 by pin 57 and is provided with the neck engaging ring 58 and pivoted lug 59 which functions in the same manner as the invention heretofore described.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

I claim:

40. 1. A bottle opener comprising a stationary handle, a pivoted handle connected thereto, an annular member carried by the pivoted handle for receiving the neck of a bottle, and bottle cap engaging means carried by the handles for engaging diametrically opposite edges of a bottle cap, said cap engaging means holding the cap stationary while the neck is tilted by the annular member upon a pivotal movement of said pivoted handle to pry the cap from the neck.

50. 2. A bottle opener comprising a stationary handle, a pivoted handle connected thereto, an annular member carried by the pivoted handle for receiving the neck of a bottle, a stationary lug carried by the stationary handle for engaging one edge of a bottle cap on the neck, and a pivoted lug carried by the stationary handle for engaging a diametrically opposite edge of the cap, said annular member tilting the neck of the bottle upon actuation of said pivoted handle,

55. 3. A pivoted lug carried by the stationary handle for engaging a diametrically opposite edge of the cap, said annular member tilting the neck of the bottle upon actuation of said pivoted handle, and said lugs cooperating to pry a cap from the neck of the bottle during such movement of the pivoted handle.

60. 4. A bottle cap remover comprising a stationary handle, a pivoted handle connected thereto, an annular member carried by the pivoted handle for receiving the neck of a bottle, a stationary lug carried by the stationary handle for engaging one edge of a bottle cap on the neck, a pivoted lug carried by the stationary handle for engaging a diametrically opposite edge of the cap, and means operatively connecting the pivoted lug to the pivoted handle for actuation by the latter, said annular member tilting the neck of the bottle by a predetermined actuation of the pivoted handle while the cap is held against said sta-

tionary lug, and said pivoted lug exerting an upward force on the cap to pry the cap from the bottle.
